ATTY'S

UNITED STATES PATENT OFFICE.

DOUGLAS A. WILSON, OF PEORIA, ILLINOIS.

DESIGN FOR A MOTOR-CULTIVATOR.

54,807.

Specification for Design.

Patented Mar. 23, 1920.

Application filed July 20, 1918. Serial No. 245,957. Term of patent 3½ years.

To all whom it may concern:

Be it known that I, DOUGLAS A. WILSON, a citizen of the United States, residing at Peoria, in the county of Peoria and State of Illinois, have invented a new, original, and ornamental Design for a Motor-Cultivator, of which the following is a specification, reference being had to the accompanying drawing, forming a part hereof.

Figure 1 represents a view in side elevation of my new design.

Fig. 2 represents a top plan view of the same.

Fig. 3 represents a front elevation of the same.

What I claim is:

The ornamental design for a motor cultivator as shown.

DOUGLAS A. WILSON.
